UNITED STATES PATENT OFFICE.

WILLIAM D. COOLIDGE, OF SCHENECTADY, NEW YORK, ASSIGNOR TO GENERAL ELECTRIC COMPANY, A CORPORATION OF NEW YORK.

ELECTRON-DISCHARGE APPARATUS AND METHOD OF OPERATING THE SAME.

1,211,376.

Specification of Letters Patent. Patented Jan. 2, 1917.

Application filed March 30, 1915. Serial No. 18,138.

To all whom it may concern:

Be it known that I, WILLIAM D. COOLIDGE, a citizen of the United States, residing at Schenectady, in the county of Schenectady, 5 State of New York, have invented certain new and useful Improvements in Electron-Discharge Apparatus and Methods of Operating the Same, of which the following is a specification.

10 The present invention comprises a method of controlling an electron discharge energized by a periodically varying voltage and an apparatus for carrying out this method.

15 My invention is particularly applicable to the operation of an X-ray device with a current of variable voltage when it is desired to select a certain part of the current wave and thus, for example, to secure rays of more uniform penetrability.

20 * In accordance with my invention an electrostatic field is established radially about the cathode in synchronism with the periodicity of the impressed voltage, this field having an electrostatic charge over an un- 25 desired range of voltage values suitable in polarity and potential to reduce or even entirely suppress the electron discharge. During the intervals that current flow is desired, for example, near the voltage peaks of each 30 current wave, the intensity and if desired, also the polarity of the field, is changed to promote the electron discharge.

35 In the specific embodiment of my invention illustrated diagrammatically an X-ray tube operated with a periodically varying current is provided, at the cathode, with means for establishing a negative field over a part of the wave interval and a positive field over another part in synchronism with the supply current.

40 Referring to the drawing, the X-ray tube 1 is connected to the secondary of a high potential transformer 2 by means of conductors 3, 3'. The cathode 4 consists of a flat spiral filament which is shown on edge. The heating current from a battery 5 is supplied by conductors 6, 6' sealed into the glass stem 7 in the manner well understood in the construction of incandescent lamps. 45 The temperature of the filament and thereby the resistance of the tube may be varied by adjusting the resistance 8 in the heating circuit. The anode 9 consists preferably of ductile tungsten. It is attached to a tube 50 10 consisting of molybdenum or iron, which

is held within a socket 11 forming part of the envelop of the tube. As described in the *Physical Review* for December, 1913, the space within the tube is evacuated to such low pressure that transfer of energy between the cathode and the anode can occur substantially independently of gas ionization, the anode being deprived of gas by the cathode discharge during the evacuation of the tube. 60

Surrounding the cathode 4 is a conductive ring 12 consisting, for example, of iron or molybdenum, and supported by a wire 12' sealed into the stem 7. This ring serves to establish an electrostatic field radially about 70 the cathode in order to control the electron discharge passing between the heated cathode and the anode when a suitable potential is impressed across these electrodes. When this focusing ring 12 is allowed to assume 75 the potential of the cathode, or a negative potential not materially higher than the potential of the cathode the radial negative field has the effect of concentrating or focusing the electron discharge upon the spot of 80 limited area on the face of the anode. When, however, the negative field is sufficiently high, the particular value depending on the potential between the cathode and the anode, the electrons are prevented 85 from leaving the neighborhood of the cathode and a discharge across the vacuous space is prevented entirely. When the electrostatic field of the focusing ring is positive, 90 the passage of the electrons from the cathode to the anode is assisted and the conductivity of the tube is thereby increased. If the electrostatic charge of the focusing ring is changed in a positive direction, that 95 is, even if it is only made less negative, the resistance of the tube is decreased.

At the beginning of each half wave of current, when the impressed voltage is low, the X-rays produced by the cathode discharge impinging on the anode are of low 100 penetrating power, or, as technically termed, the rays are "soft". As the impressed voltage approaches its maximum, the hardness of the rays increases. The soft rays in some cases are not desired and the cathode discharge over the lower voltage range consumes energy and thereby heats the anode. As the capacity of the tube is limited by the heat storage and the heat-dissipating capacity of the anode, the output of the 105 110

harder rays may be increased by reducing the production of the soft rays. In the device shown in the drawing, the ring 12 is suitably charged over desired intervals 5 through conductors 13, 14, for example, by being connected to the terminals of a battery 15.

In series with the conductors 13, 14, is a commutator consisting of two disks 17, 18, 16 which connect a source of electromotive force, for example, the battery 15, to the focusing ring so as to make the ring negative over a range of impressed voltage at the beginning of a half wave impulse, then positive over a range of current near the maximum voltage, and finally again negative as the impressed voltage drops to zero. These changes in connection are produced synchronously with the variation of the supply voltage 15 by a synchronous motor 19 connected by means of conductors 20 to the same source of energy to which the supply conductors 22 of the transformer 2 are connected. The 20 commutator disk 17 contains an insulating segment 24 of relatively great angular width, and the conductive segments 25, 26, of small angular width. The commutator 18 contains an insulating segment 27 having 25 two peripheral sections substantially equal in angular width to the conductive segments 25, 26. The conductive segments 28, 29 have an angular width substantially equal to the exposed sections of the insulating segments 24 of the commutator disk 17. These disks 30 are so arranged on the common shaft that the battery will be connected through either one or the other disk between the focusing ring 12 and the cathode 4. For example, as illustrated, the positive side of the battery is connected to the focusing ring through the conductors 13, the brushes 36 and the conductor 33. The negative terminal of the battery is connected through the brushes 37, and the conductors 14 and 3' to the cathode 4 of 45 the X-ray tube. When the brushes 36 and 37 have left the conductive segments and pass on to the insulating segments of the commutator disk 17, the brushes 31 and 34 of the 50 commutator disk 18 will have traveled to the conductive segments of this commutator disk thereby reversing the potential of the focusing ring 12. It will be noted that in this manner the potential of the focusing ring is 55 made positive during the interval that the passage of current through the X-ray tube is desired, and negative when the passage of current is to be suppressed. The size of the commutators and the distance between the 60 brushes may be varied as desired.

What I claim as new and desire to secure by Letters Patent of the United States, is:—

1. The process of selectively operating an electron discharge device fed with an energy 65 supply periodically varying in voltage which

consists in applying an electrostatic field about the cathode of said device to control the flow of current and periodically changing said electrostatic field over desired current intervals in the direction of positive 70 polarity to increase the current.

2. The process of selectively operating an X-ray tube with a current of variable voltage which consists in applying an electrostatic field radially about the cathode of 75 said tube to reduce the cathode discharge, and periodically in step with the variations of supply voltage changing said field over a range of voltages near the maximum value to increase the cathode discharge and 80 thereby to increase the generation of X-rays.

3. The process of operating an electron discharge device which consists in supplying said device with a current periodically varying in potential and in synchronism with the 85 variations of applied potential applying an electrostatic field about the cathode over selected portions of the supply current waves to increase the conductivity of said device relative to the remaining portions.

4. The process of operating with a periodically varying current an electrical discharge device having an electron-emitting cathode, an anode and an inclosing bulb evacuated to a pressure so low that evidences of positive ionization are substantially absent during the operation of the device, which consists in establishing an electrostatic field radially about the cathode, said field having negative potential high enough during intervals when no current is desired to prevent the discharge between the cathode and the anode, and periodically reducing the value of said field to or beyond zero during intervals when current flow is desired.

5. The combination of an electron discharge device comprising co-operating electrodes and a conductive member surrounding at least in part the discharge path between said electrodes, a source of variable current 110 connected to the electrodes of said tube, a source of electromotive force, means for connecting said source between the cathode and the conductive member during selected portions of each wave of supply current synchronously with the periodicity of supply current.

6. An X-ray apparatus comprising an X-ray tube having an electron-emitting cathode, a source of energy of variable voltage connected to said tube, means for establishing a discharge-controlling electrostatic field radially about the cathode over a range of current near the minimum values of the potential, and means for changing said field 125 in the direction of positive polarity over a range of current near the maximum value of the potential.

7. An X-ray apparatus comprising an X-ray tube having an incandescent cathode, a 130

source of alternating current, means for establishing a negative static field radially about the cathode over a range of current values when the potential is near the minimum value and means for reversing the polarity of the field near the maximum value of the voltage.

8. The combination of an X-ray tube in the operation of which evidences of positive ionization are substantially absent, a source of electric energy supply therefor of variable voltage, a conductor surrounding in part at least an axis passing through the cathode and the anode of said device and means operating in synchronism with the source of energy supply for charging said conductor negative over a range of current

near the minimum value of potential and positive over a range of current value near the maximum value of potential.

9. The process of selecting predetermined current intervals of an electron discharge fed with an energy supply, periodically varying in voltage which consists in applying a radial negative electrostatic field about the discharge and reducing the value of said negative field to or beyond zero synchronously with the variation of supply voltage over a desired current wave interval to reduce the resistance of the discharge path.

In witness whereof, I have hereunto set my hand this 29th day of March, 1915.

WILLIAM D. COOLIDGE
